UNITED STATES PATENT OFFICE.

SARAH L. BRUNDIDGE, OF SAVANNAH, GEORGIA.

DESIGN FOR A GIRDLE FOR WAIST FOUNDATIONS.

42,196.

Specification for Design.

Patented Feb. 27, 1912.

Application filed November 26, 1910. Serial No. 594,413. Term of patent 14 years.

To all whom it may concern:

Be it known that I, SARAH L. BRUNDIDGE, a citizen of the United States, residing at Savannah, in the county of Chatham and State of Georgia, have invented a new, original, and ornamental Design for Girdles for Waist Foundations, of which the following is a specification, reference being had to the accompanying drawing, forming part thereof.

The figure is a plan view of a girdle, showing my new design.

I claim:

The ornamental design for a girdle for waist foundations, as shown.

SARAH L. BRUNDIDGE.

Witnesses:

ELIZABETH DONNELLY,
LEE BRASWELL.
